UNITED STATES PATENT OFFICE.

JOHN F. GODFREY, OF ELKHART, INDIANA, ASSIGNOR TO THE GODFREY CONVEYOR COMPANY, OF ELKHART, INDIANA, A CORPORATION OF INDIANA.

ROPE CARRIER.

Application filed December 20, 1920. Serial No. 431,819.

To all whom it may concern:

Be it known that I, JOHN F. GODFREY, a citizen of the United States, residing at Elkhart, in the county of Elkhart and State 5 of Indiana, have invented certain new and useful Improvements in Rope Carriers, of which the following is a specification.

This invention relates to a new and improved rope carrier, and more particularly 10 to a rope carrier or support adapted for use in connection with conveyors.

In many types of conveyors one or more ropes are connected to the conveyor traveler for purposes of traction and for the operation 15 of the traveler-carrying means. It is highly desirable that means be provided to support these ropes and since the ropes are connected to the traveler, the supporting means must be adapted to permit passage 20 of the traveler.

It is an object of the present invention to provide rope carrier and supporting means adapted to be displaced to permit passage 25 of the conveyor traveler.

It is a further object to provide means of this character which are adapted to be automatically operated by the traveler and to automatically return to supporting position after the passage of the traveler.

It is an additional object to provide means associated with said supporting means and adapted to prevent lateral displacement of 30 the ropes.

Other and further objects will appear as 35 the description proceeds.

Broadly, my invention comprises a horizontally extending supporting arm pivoted adjacent the path of the conveyor and having operatively associated therewith means 40 adapted to engage a member carried by the traveler to move the arm out of the path of the traveler to permit its passage. I also provide resilient means to restore the arm to supporting position.

The invention further includes vertically placed guide rollers located within the horizontal scope of operation of the supporting arm and adapted therewith to positively prevent a lateral displacement of the ropes.

I have illustrated a preferred embodiment of my invention in the accompanying drawings, in which—

Figure 1 is a side view of a portion of the conveyor showing the conveyor traveler 55 and my rope supporting member;

Figure 2 is a plan view of Figure 1; Figure 3 is an end view of Figure 1; and Figure 4 is a detail view of the rope supporting arm.

The type of conveyor shown in the drawings comprises an I-beam support 4 upon which travel the rollers 5 carried by frames 6, the frames being connected by the links 7, 8 and 9. The traction rope 10 is connected to the ends of the links 7 and 9 and serves 60 to move the traveler along the support 4. The links 7, 8 and 9 are pivotally connected by the bolts 11 and 12 to permit the traveler to conform to curves in the track or guideway. The pulleys 13 are suspended 65 from the frames 6 by the straps 14, eyes 15 and cross bolts 16. The hoist rope 17 passes over the two pulleys 13 and intermediate 70 these pulleys supports the carrier 18. The vertical rollers 19 and 20 are carried by the 75 rod 21 supported by the bracket 22.

The bracket 23 carried by the I-beam 4 is provided with a bearing 24 at its left end as shown in Figure 3. In this bearing is supported the pivot member 25 having connected thereto the operating arm 26 and the rope supporting arm 27. The arm 27 is connected to the pivot member 25 by means of the pin 28 fitting in any one of a series of holes, this form of connection permitting 80 adjustment as to height. The upper end of the pivot member 25 carries the crank arm 29 to which is secured one end of the spring 30, the opposite end of the spring being held by the eye 31 carried by the right end 85 of the bracket 23. As best shown in Figure 3, the bearing 24 and the adjacent portion of the arm 29 are provided with coacting 90 lugs and grooves 32, 33 adapted to yieldingly maintain the crank arm normally in a 95 position parallel to the bracket 23. The supporting arm 27 is provided with the rope carrying roller 34 and the outer lip 35. To each frame 6 is bolted an engaging member 36 extending horizontally beyond the end of 100 the traveler. The intermediate link 8 carries the engaging member 37 in the plane of the members 36.

In the use of the conveyor, the traveler is moved in either direction by appropriate 105 movement of the traction rope 10. The carrier 18 is raised or lowered by movement of the hoist rope 17. As the traveler is moved on the track 4 the ropes 10 and 17 are supported upon the rollers 34 of the sup- 110

porting arms 27. They are prevented from any possible lateral displacement in one direction by the pivot member 25 and in the opposite direction by the rollers 19 and 20.

5 The upper roller 19 is adapted to receive the traction rope and the lower roller 20 the hoist rope.

It is to be noted that the rollers 19 and 20 and the supporting member 27 are located 10 in different planes so that when in supporting position the lip 35 of the supporting member extends beyond the inner face of the rollers. These several elements thus combine to jointly prevent displacement of the 15 ropes.

As the traveler approaches the supporting member 27 the member 36 of the forward frame 6 of the traveler engages the operating arm 26 and thus rotates the pivot member 25 and swings the arms 27 and 29 laterally, the arm 29 pulling against the resistance of the spring 30. This movement is sufficient to permit the arm 27 to clear the pulleys 18 during the passage of the 25 traveler.

The supporting arm assembly is retained in this position by the engagement of the arm 26 with members 36, 37 and 38 until the traveler has fully cleared the arm 27. The 30 spring 30 then serves by means of its connection with the crank arm 29 to again bring the supporting arm 27 transversely of the conveyor body. This movement occurs so closely after the passage of the traveler that 35 the arm 27 moves under the rope 17. The intergaging lugs and grooves 32, 33 serve to prevent swinging or rebound of the arm 27, and it is retained in its transverse position.

40 It is to be understood that the rollers 19 and 20, while they may be used at any point upon the conveyor, are particularly desirable at or adjacent curves or turns in the conveyor track, as shown in Figure 2. The 45 construction which has been shown is simple in design and is positive and automatic in its operation. It serves to maintain the hoisting and traction cables at their proper location adjacent the conveyor track and yet 50 readily permits passage of the conveyor traveler.

I claim:

1. In combination with a conveyor traveler and conveyor supporting means, ropes 55 associated with the traveler, and supporting means for said ropes normally interposed in the path of the traveler and adapted to be displaced by a member making operative connection with means carried by the traveler, in order to permit passage of the traveler.

2. In combination with a conveyor traveler and conveyor supporting means, ropes 60 associated with the traveler, supporting means for said ropes normally interposed in

the path of the traveler and adapted to be displaced by a member making operative connection with means carried by the traveler in order to permit passage of the traveler, and means adapted to return the supporting 70 means to normal position after passing of the traveler.

3. In combination with a conveyor traveler and conveyor supporting means, ropes 75 associated with the traveler, supporting means for said ropes adapted to be displaced to permit passage of the traveler, and means adapted to prevent lateral displacement of the ropes.

4. In combination with a conveyor traveler, a rope associated therewith, a laterally extending movable arm adapted to support the rope, and means carried by the traveler adapted to displace the arm to permit passage of the traveler and to maintain the arm 85 displaced during such passage.

5. In combination with a conveyor traveler, a rope associated therewith, a laterally extending movable arm adapted to support the rope, means carried by the traveler 90 adapted to displace the arm to permit passage of the traveler, and a spring associated with the arm and adapted to return it to supporting position after passage of the 95 traveler.

6. In combination with a conveyor traveler, a rope associated therewith, a laterally extending bracket adjacent the conveyor, an arm pivotally connected to the bracket and extending in the path of the traveler to support the rope and means adapted to displace the arm and maintain the arm displaced during passage of the traveler.

7. In combination with a conveyor traveler, a rope associated therewith, a laterally 105 extending bracket adjacent the conveyor, an arm pivotally connected to the bracket and extending in the path of the traveler to support the rope, an operating arm associated 110 with the supporting arm, and means carried by the traveler adapted to engage the operating arm to move the supporting arm and to maintain it out of the path of the traveler during passage thereof.

8. In combination with a conveyor traveler, a rope associated therewith, a laterally 115 extending bracket adjacent the conveyor, an arm pivotally connected to the bracket and extending in the path of the traveler to support the rope, an operating arm associated 120 with the supporting arm, means carried by the traveler adapted to engage the operating arm to move the supporting arm out of the path of the traveler during passage thereof, and a spring connected to the 125 bracket and the supporting arm assembly in such manner as to return the supporting arm to supporting position after passage of the traveler.

9. In combination with a conveyor trav-

eler, a rope associated therewith, a laterally extending movable arm adapted to support the rope, and vertically extending rollers adapted to prevent lateral displacement of the rope.

10. In combination with a conveyor traveler, a rope associated therewith, a laterally extending movable arm adapted to support the rope, and vertically extending rollers adapted to prevent lateral displacement of the rope, the rollers being located within the operating scope of the movable arm.

11. In combination with a conveyor traveler, conveyor supporting means, hoist and traction ropes associated with the traveler, a laterally extending bracket adjacent the conveyor support, a pivot member associated with the bracket and carrying a rope supporting arm and an operating arm, and a laterally extending engaging member carried by the traveler and adapted to engage the operating arm to move the rope supporting arm laterally during the passage of the traveler.

25. 12. In combination with a conveyor traveler, conveyor supporting means, hoist and traction ropes associated with the traveler, a laterally extending bracket adjacent the conveyor support, a pivot member associated with the bracket and carrying a rope supporting arm and an operating arm, a later-

ally extending engaging member carried by the traveler and adapted to engage the operating arm to move the rope supporting arm laterally during the passage of the traveler, 35 an operating arm associated with the supporting arm, and means carried by the traveler adapted to engage the operating arm to move the supporting arm out of the path of the traveler during passage thereof. 40

13. In combination with a conveyor traveler, conveyor supporting means, hoist and traction ropes associated with the traveler, a laterally extending bracket adjacent the conveyor support, a pivot member associated 45 with the bracket and carrying a rope supporting arm and an operating arm, a laterally extending engaging member carried by the traveler and adapted to engage the operating arm to move the rope supporting arm 50 laterally during the passage of the traveler, means carried by the traveler adapted to engage the operating arm to move the supporting arm out of the path of the traveler during passage thereof, and vertically extending rollers adapted to prevent lateral 55 displacement of the cables, the rollers being located within the horizontal operating scope of the movable arm.

Signed at Elkhart, Indiana, this 17th day 60 of December, 1920.

JOHN F. GODFREY.
